ATTORNEY.

UNITED STATES PATENT OFFICE.

CLARENCE H. NEIMYER AND VAUGHN S. GETTS, OF ST. PETERSBURG, FLORIDA.

AUTOMOBILE LOCK.

Application filed July 26, 1923. Serial No. 653,881.

To all whom it may concern:

Be it known that we, CLARENCE H. NEIMYER and VAUGHN S. GETTS, citizens of the United States of America, residing both at 5 St. Petersburg, county of Pinellas, State of Florida, have invented certain new and useful Improvements in Automobile Locks, of which the following is a specification.

This invention relates to improvements in 10 combination locks. More particularly it relates to a lock for use in connection with motor vehicles for the purpose of opening or closing the electric circuit which controls the ignition of the vaporous charge.

15 An object of the invention is to provide a combination lock which will prevent an unauthorized person from starting the car.

A further object of the invention is to provide an electric make and break device which 20 cannot be operated unless the combination is set or arranged, at a definite position which position is known only to the authorized person.

Broadly my invention comprises a series 25 of discs which are designed to be rotated or operated by the knob of the lock and when the discs are located in a definite position the switch may then be operated to either open or close the electric circuit which may 30 be either the ignition or primary circuit.

Referring to the drawings which form a part of the present specification.

Fig. 1 is an end elevational view of the graduated or dial end of the lock.

35 Fig. 2 is a longitudinal sectional view on the line 2-2 of Fig. 1 showing the interior construction and with the retaining roller in one position.

Fig. 3 is an end view of Fig. 2 showing 40 the retaining roller and the spring for actuating the same.

Fig. 4 is a detail view of the spring actuated slidable roller retaining device.

Fig. 5 is an end view of Fig. 4 substantially on the line 5-5 of Fig. 2.

Fig. 6 is a view similar to Fig. 2 but taken on a plane that is at right angles to that shown in Fig. 2.

Figs. 7, 8 and 9 are detail views of the 50 discs which make up the combination of the lock.

Fig. 10 is a detail view of the graduated fixed member of the lock.

Fig. 11 is an end view of the same and 55 Figs. 12 and 13 are detail views of the

contact elements which are operated by the knob.

Referring to the drawings in detail:

1 designates the enclosing casing to which the fixed index dial 2 is attached by the 60 screws 3. 4 is a cup-shaped casing which is releasably connected to the casing 1 by means of the threaded bolts 5. The casings 1 and 4 have their meeting inner ends covered with the flange 6 which is soldered 65 or brazed to the casing 4. 7 is a threaded stud for attaching the whole to a suitable support of the motor vehicle. 8 designates a knob or operating handle, which is provided with an inwardly extending tubular 70 member 9 that is formed with a thread 10 on its inner end to receive the disk retaining nut 11. The tubular member 9 is keyed to the rotatable graduated dial 12, which when it is turned by the knob 8 registers 75 with the zero line 13 on the fixed index dial 2 (see Fig. 1). Attached to the knob 8 is the shaft 14 by means of the threads 15. This shaft is formed with a spline 14' to receive the stud, or pin 16, on the inside of 80 tubular member 9 whereby when the knob is rotated the shaft 14 will turn the tubular member 9 and this, in turn, will rotate the graduated dial 12 into the desired position.

Located on the tubular member 9 is a 85 sleeve 17 which is formed with a flange 18, by means of which this sleeve is attached to the end 1' of the casing 1 by means of the screws 19. This sleeve is therefore, retained in a fixed position. This sleeve is provided 90 with the two threaded shouldered portions 20 and 21, while 22 and 23 designates unthreaded portions of the sleeve 17. 24 designates an unthreaded shouldered portion of the tubular member 9. Rotatably and 95 loosely mounted on the two unthreaded portions 22 and 23 are the discs 25 and 26. They are spaced from each other by means of the internally threaded washer-like parts 27 and 28, which are threaded onto the 100 threads 20 and 21. The disc 29 is formed with teeth 30 which are designed to receive the spur 31 on the tubular member 9. By means of these teeth and the spur, it will be seen that the disc 29 may be attached to the 105 rotatable tubular member in any one of the different angular positions represented by the number of recesses between the teeth 30. The combination can therefore be readily changed as desired.

The disc 25 is provided with a projection 31' and a groove 32. The disc 26 is provided with two projections 33 and 34 and a groove 35. The disc 29 is provided with a projection 36 and a groove 37.

The projection 31 on the tubular member 9 passes through the groove 38 when the parts are assembled. After the disc 25 is put in place the washer 27 is threaded onto the sleeve 17 then the disc 26 is slipped onto this sleeve, then the washer 28 is threaded onto the sleeve; then the disk 29 is placed on the sleeve 17 in any desired position by having the spur 31 enter any one of the recesses between the teeth 30. The nut 11 is now threaded onto the sleeve. This completes the assembly of the combination part of the lock.

In order to cause the grooves 32, 35 and 37 in the discs, 25, 26 and 29 to register they are turned by means of the knob 8. The projections 36, 33, 34 and 31' permitting one disc to drive the other in the well known manner of combination locks; a certain number of degrees or spaces. As indicated by the graduated dial 12 with reference to the zero line 13, first, in one direction of rotation, and then in the other. As for example; to the right 25 spaces; then to the left 30 spaces and then to the right 36 spaces when all of the three grooves 32, 35 and 37 are in alignment. The grooves are designed to receive the part 38' of the right angular shaped piece 39 shown in Figs. 4 and 5. This piece is slidably mounted in the channels or grooves 40 and 41 which are attached to the casing 4. The channel 40, it will be observed, is longer than the channel 41. In the channel 40 is located the arm 38'. In the channel 41 is located the end 42 of the piece 39, see Fig. 5. This piece is retained in place by means of the two small blocks 43 and 44 which are provided with openings to receive cotter pins 45 and 46 which pass through openings in the side pieces of the channels 40 and 41, see Fig. 3. The piece 39 is formed with an opening 47. In this opening is located a roller 48 by means of the pin 49. Also extending through this opening is the inner end of the shaft 14. This shaft is formed with a shoulder 14' against which rests the block 50 which is formed with an opening 51 therethrough to receive the shaft 14. This block is composed of a piece of metal 52 which is formed with a sleeve part 53. 54 is a piece of insulation having a collar portion 55 which receives the metal contact piece 56. The piece 56 is therefore insulated from the shaft 14. The piece of metal 52 is formed with two recesses 52' and 52'' to receive the roller 48 for retaining the shaft 14 in two different positions for opening or closing the circuit which will be explained.

68 For retaining the roller seated in either

one of these recesses and yet permit it to pass from one recess to another over the raised intermediate part 52'', a spring 57 is employed, one end of which is attached to the piece 39 at 39' and its other end is attached to the casing 1 by means of the cotter pin 45, see Figs. 3 and 5.

When the three grooves 32, 35, and 37 are in alignment as shown in Fig. 2 the part 38' can then be moved laterally or diametrically 75 of the casing when the roller 48 passes from one recess to another over the projection 52'' to open or close the electric circuit as indicated by the dotted line position 8' of the knob.

Referring now to the electrical connections, 58 and 59 designate two brushes which are attached to the casing 1 by means of the brackets 60 and 61 which are riveted thereto at 62. The brackets are insulated from the casing and from the terminal blocks 63 by the strips of fiber or other material 64. The wire terminals 65 are connected to the blocks 63 by the set screws 66, screws 67 serve to bind the brushes 58 and 59, the brackets 60 and 61; the strips of insulation 64 firmly together.

The two nuts 68 and 69 on the threaded end of the shaft 14 serve to retain the pieces 52, 54 and 56 thereon.

The brushes 58 and 59 see Fig. 6, are in contact with the piece of insulation 54, or in other words the circuit between the terminals 65 is open. When the combination knob 8 is turned to fit the combination to align the grooves 32, 35, and 37 of the discs, see Fig. 2, then the knob 8 can be drawn outward into the dotted line position 8' to bring the metal piece 56 into contact with the two brushes 58 and 59, thus closing the circuit as readily understood. It is also clear that the shaft 14 which carries the recessed block 52 cannot be reciprocated to permit the roller 48 to pass over the projection 52'' unless the grooves 32, 35, and 37 are in alignment to permit the part 38' to enter them all. In any other position the device is locked.

It will be observed that the tubular member 9 is keyed to the graduated dial 12 at 12'.

What we claim is:

1. A combination lock comprising an enclosing casing, a shaft rotatably supported therein, a reference dial secured to the casing, a graduated dial secured to the shaft and movable on the reference dial, a plurality of discs and each having a groove in its edge, a projection on each disc for operating one disc from the other for aligning the grooves, electric terminal brushes attached to the casing, a contact part on the shaft for closing the circuit from one brush to the other, and spring controlled means for entering the aligned grooves to permit the shaft to be moved in an axial direction to bring the contact part between the brushes.

said means including a movable member, a spring for retaining the member normally in the grooves and a projection on the shaft for moving the movable member out of grooves.

5 2. In a switch device, the combination, of a rotatable and axially movable shaft, means for opening or closing the switch including a member movable relatively to the shaft, a block on the shaft having a plurality of recesses and a projection between the recesses, a part on the movable member for engaging the projection to cause the block to move the movable member and the part which engages the projection to drop into one of the recesses for retaining the shaft in its axially adjusted position, contact brushes and a part on the shaft engaging the brushes when the shaft is axially moved.

10 3. In a combination lock switch device, a casing, channel members thereon, a member having its ends located in the channel members, and of a length to permit it to move laterally of the channels, an axially movable shaft, means thereon for engaging the member for moving it laterally in the channels when the shaft is moved axially, a plurality of rotatable discs each having a groove in its edge, means for aligning the grooves when the shaft is rotated to permit a part of the member to enter the aligned grooves, whereby the same can move laterally, electric terminals and a contact block on the shaft for engaging the terminals.

15 4. In a combination lock switch device, a casing, channel members therein, a member having its ends located in the channel members, and of a length to permit it to move laterally of the channels, an axially movable shaft, means thereon for engaging the member for moving it laterally in the channels when the shaft is moved axially, a plurality of rotatable discs each having a groove in its edge, means for aligning the grooves when the shaft is rotated to permit a part of the member to enter the aligned grooves, whereby the same can move laterally, electric terminals and a contact block on the shaft for engaging the terminals, and a spring device for retaining the laterally movable member normally drawn towards the shaft.

20 5. In a combination lock switch device, a casing, channel members thereon, a member having its ends located in the channel members, and of a length to permit it to move laterally of the channels, an axially movable shaft, means thereon for engaging the member for moving it laterally in the channels when the shaft is moved axially, a plurality of rotatable discs each having a groove in its edge, means for aligning the grooves when the shaft is rotated to permit a part of the member to enter the aligned grooves, whereby the same can move laterally, electric terminals and a contact block on the

shaft for engaging the terminals, one of the discs having means thereon to permit it to be removably attached to the shaft in different angular positions for varying the combination of the lock as described.

25 6. In a combination lock and electric switch, a splined shaft, a tubular member, a projection on the member entering the spline for turning the same, a sleeve having a fixed position relative to the tubular member and having a plurality of shouldered portions, discs rotatable on the portions, spacing means for the discs, another disc having means thereon for attachment to the tubular member in different angular positions, each disc having a groove in its edge the latter disc serving to operate the rotatable discs on the sleeve for aligning the grooves, a member for entering the grooves when aligned to permit the shaft to move axially, and cooperating parts on the shaft and member to move the member into the grooves when aligned but are inoperative when the grooves are not aligned.

30 7. In a combination lock and electric switch, an enclosing casing, electric terminals on the casing, contact members on the shaft, a splined shaft, a tubular member, a projection on the member entering the spline for turning the same, a sleeve having a fixed position relative to the tubular member and having a plurality of shouldered portions, discs rotatable on the portions, spacing means for the discs, another disc having means thereon for attachment to the tubular member in different angular positions, each disc having a groove in its edge, the latter disc serving to operate the rotatable discs on the sleeve for aligning the grooves, a member for entering the grooves when aligned to permit the shaft to move axially and open or close the electric circuit, and cooperating parts on the shaft and member to move the member into the grooves when aligned but are inoperative when the grooves are not aligned, said parts including a roller on the member and recessed portions on the shaft with a projection between the portion for engaging the roller to move the member into the grooves, and means for retaining the shaft in its adjusted position.

35 8. An electric combination lock comprising an enclosing casing, a rotatable and slideable shaft in said casing, electric terminals attached to the casing, a block on the shaft having a conducting and an insulating part for engaging the terminals for closing or opening the circuit, means for permitting the shaft to be moved axially for closing or opening the circuit, said means including a plurality of grooved discs, an angular shaped member having a part for entering the grooves when aligned by rotating the shaft, and another part engaging the block

for moving the member into the grooves whereby the shaft may be moved axially for closing or opening the circuit.

9. An electric combination lock comprising an enclosing casing, a rotatable and slideable shaft in said casing, electric terminals attached to the casing, a block on the shaft having a conducting and an insulating part for engaging the terminals for closing or opening the circuit, means for permitting the shaft to be moved axially for closing or opening the circuit, said means including a plurality of grooved discs, an angular shaped member having a

part for entering the grooves when aligned 15 by rotating the shaft, and another part engaging the block for moving the member into the grooves whereby the shaft may be moved axially for closing or opening the circuit, the block having recesses and an 20 elevation between the same, and the member having a roller which engages the elevation for moving the part of the member into the grooves and for seating in the recesses to retain the switch in its adjusted closed or 25 open position.
